UNITED STATES PATENT OFFICE.

MARY DRESBACH, OF NEW HAVEN, CONNECTICUT.

BRASSIÈRE.

1,385,672.

Specification of Letters Patent. Patented July 26, 1921.

Application filed December 6, 1920. Serial No. 428,507.

To all whom it may concern:

Be it known that I, MARY DRESBACH, a citizen of the United States, residing at New Haven, in the county of New Haven and State of Connecticut, have invented a new and useful Improvement in Brassières; and I do hereby declare the following, when taken in connection with the accompanying drawings and the characters of reference 10 marked thereon, to be a full, clear, and exact description of the same, and which said drawings constitute part of this application, and represent, in—

Figure 1, a plan view of a brassière constructed in accordance with my invention.

Fig. 2, a broken view of one end illustrating a modified form of my invention.

This invention relates to an improvement in brassières. In the more general constructions of brassières they encircle the body and furthermore are usually provided with shoulder straps, both features of which restrict to some extent the movements of the wearer.

25 The object of this invention is to provide a brassière which is attached to the corset at each side and near the upper edge and a brassière which includes triangular frames which give the desired conformation and 30 which are connected at the center by a spring so as to provide for the free movement of the wearer and the invention consists in the construction and arrangement of parts as hereinafter described and particularly recited in the claims.

In carrying out my invention I form the brassière from suitable material and properly gored to give the desired form. Preferably and as shown the brassière is divided 40 at the center forming an opening in the upper edge for the insertion of an elastic section, 3. Connected with the top at each side of the center are triangular frames 4 formed from spring metal and inclosed by strips of fabric 5 preferably corresponding to the material from which the main portion 6 of the brassière is formed. The inner ends of these frames are connected by a coil spring 7 and the outer ends are provided with

hooks 8 or other suitable fastening devices 50 whereby the ends may be connected with the side sections of an ordinary corset and the brassière is provided at its lower edge with a series of eyes 9 or other means by which the brassière may be fastened to the 55 front of the corset. The metal frames 4 give the desired support and conformation and the spring connecting the frames permits the free movement of the wearer. Instead of arranging the metal frames with 60 the points extending downward as in Fig. 1 in the drawings, the frames may be reversed as indicated by Fig. 2 in which case the points of the angles will extend up beneath the arms, a desirable feature when worn 65 with certain types of garments.

I claim:

1. A brassière provided at opposite sides with means for attachment to the sides of the corset combined with triangular metal 70 frames arranged at each side of the center the inner ends of the frames connected by a coil spring.

2. A brassière provided at the center of its upper edge with an elastic section combined with triangular metal frames connected with the upper edge of the brassière, said frames provided at their outer edges with means whereby they are connected to the corset, the inner ends of the frames 80 connected by a coil spring.

3. A brassière provided at the center of its upper edge with an elastic section combined with triangular metal frames connected with the upper edge of the brassière, said frames provided at their outer edges with means whereby they are connected to the corset, the inner ends of the frames connected by a coil spring and means for connecting the lower edges of the device with the 90 upper portion of the corset.

In testimony whereof, I have signed this specification in the presence of two subscribing witnesses.

MARY DRESBACH.

Witnesses:

FREDERIC C. EARLE,
M. P. NICHOLS.
